ATTACHMENT FOR APERTURES OF CHECK-CONTROLLED APPARATUS

Filed Nov. 16, 1936

UNITED STATES PATENT OFFICE

2,141,745

ATTACHMENT FOR APERTURES OF CHECK-
CONTROLLED APPARATUSOscar H. Goetz, Park Ridge, Ill., assignor to
Goetz Telephone Slug Service, Inc., Chicago,
Ill., a corporation of Illinois

Application November 16, 1936, Serial No. 111,077

8 Claims. (Cl. 194—4)

My invention relates to apertures for check controlled apparatus, such as telephone sub-station instruments, and is concerned particularly with an attachment for converting the apparatus from a coin controlled device into a slug controlled device to thereby prevent surreptitious operation of the device with false coins.

Many coin-controlled devices, such as the coin collectors of telephone sub-stations, are provided with chutes protected by a housing which contains a circular pocket opening into the front face of the housing and through which a coin is inserted flat and brought into registration with the coin chute. Broadly, the present invention has for its principal object the conversion of a coin pocket or aperture of this type into a slug receiving aperture by an attachment which may be secured to the existing coin housing without mutilating that housing in any manner.

More specifically, the object of the present invention resides in the provision of a new and simplified form of guard plate for the coin aperture, and the provision of new and improved means for securing said guard plate to the housing.

Another object of the invention resides in the provision of a coin chute conversion attachment that may be economically manufactured, and one in which the guard portion thereof may be easily replaceable with respect to the means securing it to the housing, thereby readily permitting an authorized person to change the code by which the coin apertures are guarded, so that an entirely different set of slugs must be used to operate the device.

Other features of the invention consist in certain novel combinations and arrangements of parts as will hereinafter be more fully set forth and claimed.

In describing my invention, reference is had to the accompanying drawing, wherein there is illustrated the preferred physical embodiment of the invention, and in which:

Figure 1 is a front elevational view of a typical telephone pay station showing my invention associated with one of the coin receiving apertures;

Figure 2 is a fragmentary front elevational view on a larger scale, showing the coin receiving housing which is mounted on top of the coin box and illustrating my improved attachment secured thereto;

Figure 3 is a fragmentary plan view of the device of Figure 2;

Figure 4 is a side elevational view of the device of Figures 2 and 3, parts being broken away;

Figure 5 is a partial vertical sectional view through the means or wedge securing the guard plate to the housing; and

Figure 6 is a longitudinal sectional view taken

substantially on the plane of the line 6—6 of Figure 3.

While the present invention has its principal utility in connection with telephone pay stations, and is to be described in connection with such devices, it will be understood that it also has utility in connection with vending machines and other coin or slug controlled apparatus.

Referring now in detail to the drawing, the telephone pay station illustrated in Figure 1 comprises the usual coin receiving box B having one or more coin chutes opening into the top of the box, one such chute being indicated at 7 in Figure 4. The upper ends of the chutes are covered by a coin receiving housing 8 having the apertures 9, 10 and 11 in the front face 12 thereof. Each aperture opens into a downwardly extending passageway or chute which is substantially co-extensive with the corresponding coin chute in the box B, one of these upper 10 passageways being indicated at 13 in Figure 4. A small hole 14^a is usually provided to open into each chute passageway 13 through the back wall 14 of the housing 8. The housing 8 is intended to represent a standard construction of coin receiving housing mounted on the coin receiving box B. Such housing may be a unitary casting. In ordinary practice, however, the housing consists of front and back sections riveted together and provided with flanges 15 and 16, respectively, which are riveted to the top of the box B. As shown, the front face 12, the top wall 17 and the side walls 18 of the housing are of unitary construction, and the side walls are preferably inclined upwardly and inwardly. Also, it will be 15 noted, that the free marginal edges of side walls 18 project beyond back wall 14 and extend upwardly and inwardly from the outer marginal edge of flange 16. This provides, in effect, a substantially triangular shaped flange 18^a, which 20 projects outwardly beyond back wall 14. Numerals appearing through the apertures 9, 10 and 11 designate that these apertures are for receiving 25 5¢, 10¢ and 25¢ coins, respectively. It is the customary practice to convert only the 5¢ or 30 nickel aperture to slug use, and accordingly the invention will be described in connection with this aperture, although it will be understood that the invention might also be adapted to aperture 10. 35

In adapting aperture 9 to the exclusive reception of coded slugs, I place an attachment device on housing 8, and in registration with aperture 9. This attachment device includes an angle plate 20 having one leg 21 thereof abutting front 40 face 12 of housing 8, and the other leg 22 disposed in abutting engagement with the adjacent side wall 18 and flange 18^a of such housing. The plate may be formed of sheet metal, 45 or any other suitable or preferred material, and 50

leg 21 thereof is provided with an aperture 23, which has a diameter substantially the same as the diameter of aperture 9, with which it is adapted to register. At the time of formation 5 of aperture 23, a multiplicity of projections or teeth 24 are also formed peripherally thereof, with such multiplicity of teeth preferably uniformly spaced. These teeth are then bent inwardly with respect to leg 21 of plate 20 and 10 are adapted to extend into aperture 9 and seat on wall 25 thereof. Aperture 23 and teeth 24, therefore provide a coded aperture in registration with aperture 9 for the reception of a peripherally coded slug such, for example, as the 15 coded slug shown in my Patent No. 2,008,415, granted July 16, 1935. Plate 20 is positively clamped to housing 8 by clamping means, designated generally at 28, which will now be described.

Clamping means 28 is of generally wedge-shape configuration and, may be formed of any suitable or preferred metal. The front face 29 of member 28 is substantially perpendicular to the base 30, while the rear face 31 is inclined 25 inwardly from base 30 to the top face 33. A slot 34, extending inwardly from front face 29 transversely of said member, is of such length as to open through base 30 and top face 33. The rear or transverse wall 35 of said slot conforms 30 to the taper or inclination of rear wall 31 and member 28 is, therefore, provided with a substantially triangularly shaped slot. By reason of slot 34, wedge member 28 is of substantially U-shaped configuration and when flange 18^a and leg 22 of plate 20 are engaged in said slot in the manner hereinafter described, one leg 36 of said member will be disposed in rear of flange 18^a, while the other leg 37 of the member will be disposed in abutting engagement with the outer surface of leg 22 of plate 20. A recess 38 formed 40 in leg 37 of member 28 extends from the base thereof to the inclined wall 35 of slot 34, and is adapted to receive a cooperating bead or rib 39, pressed outwardly from leg 22 of plate 20 and extending from the base thereof to the inclined marginal edge 40 of said plate. In this connection, it will be noted that marginal edge 40 of plate 20, as well as the free marginal edge of flange 18^a and the rear wall 35 of slot 34, 45 all have the same inclination with respect to each other and all terminate in substantially the same plane. The recess 38 and rib 39 are slightly inclined from the perpendicular toward the inclined marginal edge 40 and wall 35 of plate 50 20 and member 28, respectively, and as the member 28 is applied to plate 20 and flange 18^a by engaging the upper edges thereof in slot 34 and then sliding said member downwardly relatively to the plate and flange, it will be noted that the 55 engagement of recess 38 and rib 39 in conjunction with the engagement of the marginal edges of plate 20 and flange 18^a with wall 35 of member 28 will set up a wedging action which will effectively clamp plate 20 on housing 8. Preferably, the angle which leg 22 makes with the 60 leg 21 of plate 20 is slightly less than a right angle to assure that plate 20 will bear firmly against housing 8.

To prevent unauthorized removal of clamping 70 member 28 and angle plate 20 from housing 8, the leg 36 of member 28 is provided with a threaded aperture 41 for receiving a bolt or set screw 42. Shank 43 of bolt 42 bears against a reinforcing member 44, which is secured to the 75 inner surface of flange 18^a of housing 8 in any

suitable or preferred manner, and thereby rigidly clamps member 28 to housing 8 and restrains its removal therefrom. The top face 45 of bolt 42 is perfectly plain, the usual transverse slot of such bolts being omitted in the present case, 5 and the outer periphery of the head 47 of the bolt is provided with a plurality of spaced slots 48. These slots are preferably spaced around the outer periphery of head 47 in such manner as to permit the use of a special wrench only 10 having the space between the jaws thereof conforming with the space between the slots. In a number of installations of the present invention, therefore, it is also possible to employ a plurality of bolts 42, each having a varied space 15 between the slots 48 thereof, so that no one wrench can be employed upon each of the bolts. This will eliminate, therefore, to a considerable extent, any unauthorized removal of plate 20 and clamping member 28 from housing 8. 20

In addition to the provision of bolt 42 for preventing unauthorized removal of plate 20 from housing 8, means is also provided to frustrate any attempt which might be made to insert an instrument between leg 21 of plate 20 25 and front wall 12 of housing 8, to thereby bend leg 21 out of its plane normal to front wall 12 for the purpose of inserting a spurious coin between the plate and the front wall of the housing, and into aperture 9. Such means comprises 30 a substantially U-shaped member 50, one leg 51 of which is formed integrally with the upper marginal edge of leg 21 of plate 20. Transverse portion 52 of member 50 seats on top wall 17 of housing 8, while the leg 53 of member 50 extends 35 downwardly for a relatively short distance behind top wall 17 of the housing and is preferably bent slightly inwardly therebeneath, as shown. Plate 20 is, therefore, clamped at opposite corners to housing 8, by members 50 and 28, and leg 21 is effectively strengthened against bending. It may also here be stated that, especially in sub-station installations, the working space between the instrument and its supporting wall is relatively small. Consequently, it is not possible to insert almost any type of tool in such space to remove member 50 or bolt 42 from the present device. Therefore, after the present device is installed on the instrument, the member 50 and bolt 42 will effectively accomplish 45 their purposes above described, and can only be removed by an authorized person having the proper tools. 50

While a preferred embodiment of my invention 55 has been illustrated and described herein, by way of example, it will be obvious that changes may be made therein within the spirit and scope of the invention and, therefore, I do not limit my invention to the form herein disclosed, except 60 insofar as it may be so limited in the appended claims.

I claim:

1. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture 65 into a slug receiving aperture comprising a guard member mounted on said housing and provided with a coded aperture registering with said coin aperture, and means receiving portions of said flange and guard and slideable in a plane disposed 70 75 95

parallel to the plane of said flange to secure said guard to said flange.

2. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture into a slug receiving aperture comprising an angle plate mounted upon said housing, one leg of said plate abutting the front wall of said housing and having a coded aperture registering with said coin aperture, and means comprising a substantially U-shaped member receiving portions of said flange and the other leg of said plate and securing said plate to said flange.

3. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture into a slug receiving aperture comprising an angle plate mounted upon said housing, said plate having one leg thereof abutting the front wall of the housing and having a coded aperture registering with said coin aperture, the other leg of said plate abutting the side wall of said housing and having its free marginal edge terminating in the plane of the free marginal edge of said flange, and means embracing the free marginal edges of said flange and the latter leg of said plate and securing said plate to said housing.

4. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture into a slug receiving aperture comprising an angle plate mounted upon said housing, said plate having one leg thereof abutting the front wall of the housing and having a coded aperture registering with said coin aperture, the other leg of said plate abutting the side wall of said housing and having its free marginal edge terminating in the plane of the free marginal edge of said flange, means embracing the free marginal edges of said flange and the latter leg of said plate and securing said plate to said housing, and means associated with said last named means and said flange and operative to restrain unauthorized removal of said last named means from said plate and flange.

5. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture into a slug receiving aperture comprising an angle plate, said plate having one leg thereof abutting the front wall of the housing and having a coded aperture registering with said coin aperture, the other leg of said plate abutting said side wall of the housing, means embracing said flange and the latter leg of said plate, and cooperating means carried by said last named means and the latter

leg of said plate and operative to set up a wedging action between the plate, flange and said embracing means to secure said plate to said housing.

6. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture into a slug receiving aperture comprising an angle plate mounted upon said housing, said plate having one leg thereof abutting the front wall of the housing and having a coded aperture registering with said coin aperture, the other leg of said plate abutting said side wall of the housing, a U-shaped member adapted to embrace said flange and the latter leg of said plate, a recess of appreciable length formed in one leg of said member, and a rib formed in the latter leg of said plate, said rib and said recess being engageable by relative sliding movement of said member with respect to said flange and plate and thereby securing said plate to said flange.

7. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture into a slug receiving aperture comprising an angle plate mounted upon said housing, said plate having one leg thereof abutting the front wall of said housing and having a coded aperture registering with said coin aperture, the other leg of said plate abutting the side wall of the housing, means associated with the first leg of said plate and with said housing and operative to restrain bending of said leg out of its plane normal to the front wall of the housing, and means associated with said flange and the second leg of said plate and securing said plate to said housing.

8. The combination with a coin receiving housing comprising front and rear walls, and a side wall formed integrally with said front wall and having a portion thereof providing a flange projecting beyond said rear wall, said front wall having an aperture therein intended to receive coins, of means for converting said coin aperture into a slug receiving aperture comprising an angle plate mounted upon said housing, said plate having one leg thereof abutting the front wall of said housing and having a coded aperture registering with said coin aperture, the other leg of said plate abutting the side wall of the housing, means operative to restrain bending of said first named leg of said plate out of a plane normal to the plane of the front wall of the housing comprising a U-shaped member having one leg thereof formed integrally with the first leg of said plate, the transverse portion of said U-shaped member seating on the top wall of said housing, and the other leg of said member being disposed in rear of and engaging beneath the top wall of the housing, and means associated with said flange and the second leg of said plate and securing said plate to said housing.
